United States Patent

Des. 236,046
Patented July 29, 1975

236,046

CHAIR OR SIMILAR ARTICLE

Jonathan Ginat, New York, N.Y. (6% A.C.I. Industries, Inc., 38-60 Review Ave., Long Island City, N.Y. 11100)

Filed Oct. 16, 1973, Ser. No. 406,819

Term of patent 14 years

Int. Cl. D6—01

U.S. Cl. D6—49

The single drawing figure is a perspective view of a chair showing my new design, the far side being a mirror image of the near side.

I claim:

The ornamental design for a chair or similar article, as shown and described.
